ARCH SUPPORT

Charles B. Sheridan, Rochester, N. Y., assignor of
one-half to Joseph H. Stiffler, Rochester, N. Y.

Application November 29, 1947, Serial No. 788,860

2 Claims. (Cl. 36—71)

1

Fallen arches are of frequent occurrence and interfere with walking. I have invented an arch support that can be inserted in the shoe and will support a fallen arch.

I have invented an arch support that can easily be adjusted to raise the fallen arch much or little as the circumstances may require.

I have invented an arch support that is simple in construction and can be cheaply and easily made and can be adapted to a great variety of conditions that may exist in the foot that has the fallen arch.

These and other objects of the invention will be illustrated in the drawing, described in the specification and pointed out in the claims at 15 the end thereof.

In the drawing Fig. 1 is a bottom plan view of the arch support. Fig. 2 is a longitudinal section on the line 2x2x of Fig. 1.

Fig. 3 is a transverse section on the line 3x3x of Fig. 1.

Fig. 4 is a transverse section on the line 4x4x of Fig. 1.

Fig. 5 is a detailed view of a shim that will be inserted in the arch support for the purpose of raising the arch.

In the drawings reference numeral 1 indicates a leather covering for the arch support.

2 and 3 indicate the sections of the metal plates which are connected by rivets 4 and 5 to the leather cover. These sections of the metal plate are separated on the dotted line 6, indicated in Fig. 1 and are indicated by the open space in Fig. 2. 7 indicates the metal cruciform plate that connects the two sections 2 and 3. It is connected to each section by two rivets, 8 and 9 and 10 and 11, these plates 2 and 3 are as wide or nearly as wide as the sole of the foot.

The cruciform plate has a central area which is substantially square and from this central area branches out four extensions, 11a, 12, 13 and 14, each of which is substantially the same area as is the central section.

The extensions 11 and 13 and the central part of the cruciform plate overlap the open space 6, that is left between the two sections.

Between this central part and the extensions 11 and 13 of the cruciform plate and the two sections 2 and 3, can be inserted a metal plate 15, which is called a shim. This shim will raise the central part of the arch support according to its thickness and the thicker the shim the more the central part of the arch support will be raised and the more effective the arch support will be in supporting the fallen arch if it needs the addi-

tional support given to it by the thicker shim. This shim has an upturned end and is inserted from the left hand side of Fig. 3 and the upper side of Fig. 1. The curve of the shim conforms to the upturned side shown in Fig. 3. The shim can be long or short and according as its length as shown in Fig. 5 as compared with Fig. 3, it will raise the arch support part of the way across or all the way across as may be desired, and it will raise the arch or that portion of the arch in which support is needed that is to say a short shim will tilt both plates of the arch support on the one side on which it is inserted without raising the other side. A long shim will raise the arch support all the way across.

By making the leather cover long and extending beyond the plates 2 and 3 and putting a dividing line between the two plates 2 and 3, and by connecting the plates with the cruciform plate that is comparatively short, I give a degree of elasticity to the arch support that would otherwise not be obtained.

I claim:

1. In an arch support the combination of an insole, two metal plates substantially as wide as the sole of the foot under the insole, said plates having adjacent parallel edges extending across the insole and said plates extending forward and back under the insole from said edges, said plates being attached to the insole from said edges, each of said plates being bent up at the end of the parallel edges at the inside of the insole, a metal cruciform plate having a central part and having four sections extending therefrom at equal angles, two of said sections and the central part being located under the parallel edges of the first mentioned plates, one of said sections extending toward the inside of the insole and being bent up to conform to the bend in the two plates, the other two sections extending transverse to the parallel edges and being attached only at their outer ends to said first named plates whereby a metal strip in the form of a shim may be inserted transversely across said insole between the parallel edges of said plates and the first-named two sections of said cruciform plate, to provide a desired arching effect.

2. In an arch support the combination of an insole, two metal plates substantially as wide as the sole of the foot under the insole, said plates having adjacent parallel edges extending across the insole and said plates extending forward and back under the insole from said edges, said plates being attached to the insole remote from the

parallel edges, each of said plates being bent up at the end of the parallel edges at the inside of the insole, a metal cruciform plate having a central part and having four sections extending therefrom at equal angles, two of said sections and the central part being located under the parallel edges of the first mentioned plates, one of said sections extending toward the inside of the insole and being bent up to conform to the bend in the two plates, the other two sections 10 extending transverse to the parallel edges and being attached at their outer ends only to said first named plates, a shim inserted between the plates from the side on which they are bent up, said shim being bent up at one end to conform 15 to the bent up portions of the two plates and the

bent sections of the cruciform plate, said shim also being wide enough to overlap the said two metal plates.

CHARLES B. SHERIDAN.
